UNITED STATES PATENT OFFICE.

MILO E. HUTH, OF ALLIANCE, OHIO.

AMUSEMENT DEVICE.

Application filed June 2, 1927. Serial No. 195,977.

This invention relates to amusement devices such as are provided in amusement parks and the like.

The object of the invention is to provide a device requiring skill by the operator, in which a series of targets is provided, each having a slot or aperture into which a projectile such as a coin is adapted to be discharged by a pistol constructed for the purpose, the target being so arranged that when a coin enters the aperture it closes the circuit to an electric light adjacent to the target, signalling to the operator that he has made a bull's-eye.

13 An embodiment of the invention is illustrated in the accompanying drawings, in which

Figure 1 is a front elevation of the improved amusement device;

20 Fig. 2, an end elevation of the same;

Fig. 3, a transverse sectional view through the target;

Fig. 4, a rear elevation of the target; and

Fig. 5, a front elevation of the same.

25 Similar numerals refer to similar parts throughout the drawings.

The device may comprise a stand 1 having the step or offset 2 in rear of which are located the targets indicated generally at 3.

30 Each of these targets is formed of a rectangular sheet of rubber or the like connected to the spaced horizontal rails 4 and 5 and provided with the central opening 6.

The central portion of the target may be

35 formed of a removable sheet 7 of the same material, having a central vertical slot 8 and adapted to have its corners inserted into the eyes 9 located upon the sheet 3.

An incandescent lamp 10 is located above 40 each of the targets 3 and a plurality of shelves or steps 11 are provided on the stand above the targets and lamps for displaying prizes to be given to those making bull's-eyes.

45 A vertical tube 12 is located in rear of each target, having the forwardly curved upper end portion 13 communicating with the aperture 6, the lower end of the tube being normally closed by a plate 14 pivoted as at 15, at one side of the bottom of the tube and provided with the contact arm 17 beyond said pivotal point.

50 One wire 18, in the circuit to the corresponding lamp 10, is connected to the pivoted plate 14.

A contact arm 19 is pivoted as at 20

through the rail 4 and normally held down against the pin 21 by means of a spring 22.

The normal position of the contact arms 17 and 19 is shown in full lines in Fig. 4, 60 these contact arms being slightly spaced apart. The other wire 23 of the lamp circuit is connected to the contact arm 19.

The pivotal portion 20 of the contact arm 19 extends through the rail 4 and is provided at its forward end with an angular portion 24, forming an operating lever by means of which the contact arm 19 may be rocked to the dotted line position shown in Fig. 4, in contact with the pin 25. 70

In this position it will be seen that the plate 14 is permitted to drop to the dotted line position shown in the same figure into contact with the pin 26.

Spaced in front of the stand 1, and parallel therewith, is provided a counter 27 to which may be attached, as by chains 28, pistols 29 corresponding in number and position to the targets. 75

These pistols are adapted to propel coins 80 from the barrels thereof and may be of the type shown in Norris Patent No. 1,510,899 of October 7, 1924.

In operating the device the operator places a coin in the pistol 29 and holds the 85 pistol in the position shown in Fig. 2, aiming at the slot 8 in the corresponding target. When the trigger of the pistol is pulled the coin is released and discharged toward the target. 90

Assuming that the coin enters the slot in the target, it will drop through the tube 13 and rest upon the pivoted plate 14. The weight of the coin is just sufficient to tilt the plate 14 enough to bring the contact arm 17 95 thereon into engagement with the contact arm 19, closing the circuit to the corresponding lamp 10.

However, the weight of the coin is not sufficient to swing the plate 14 downward 100 enough to permit the coin to be released, thus maintaining a closed circuit to the lamp and giving a signal that a bull's-eye has been made upon this target.

By rocking the handle 24 downward, the 105 contact arm 19 will be raised into the dotted line position shown in Fig. 4 and the weight of the coin will be sufficient to rock the plate 14 into the dotted line position, permitting the coin to drop into the conical sack 30 and through the open lower end 31 thereof into the box or receptacle 32. 110

2
When the lever 21 is released, the contact bars and plate 14 will resume the normal position shown in full lines in Fig. 4, the spring 22 pulling the arm 19 back into normal position while the contact arm 17 and plate 14 will by gravity swing into this position.

Although the slot 8 is shown in a removable plate 7 in the center of the target, this slot may be formed in the larger plate 3. However, this removable plate is provided in order that other similar plates having larger or smaller slots may be substituted therefor to accommodate varying conditions and circumstances.

I claim:

1. A target including a sheet of rubber and the like having an aperture therein, a substantially vertical tube communicating at its upper portion with said aperture, a pivoted plate normally closing the lower end of the tube, a contact arm fixed upon said pivoted plate, an electrically operated signal associated with the target, a second pivoted contact arm adjacent to the first named contact arm, means for normally holding the second contact arm against movement, a circuit connected to the signal, said circuit being broken and connected to both pivoted contact arms, whereby a projectile entering the tube through said aperture will fall upon the pivoted plate and tilt the same to move the first named pivoted arm into contact with the second pivoted arm to close the circuit to the signal, and means for tilting the second pivoted arm to permit the pivoted plate to swing downward to release the projectile therefrom.

2. A target including a sheet of rubber and the like having an aperture therein, a substantially vertical tube communicating at its upper portion with said aperture, a pivoted plate normally closing the lower end of the tube, an electrically operated signal associated with the target, a circuit connected to the signal, circuit closing means in the circuit arranged to be operated by said pivoted plate, means whereby a projectile entering the tube through said aperture will fall upon the pivoted plate and tilt the same to close said circuit closing means, means for releasing the pivoted plate to permit the projectile to fall therefrom, and means for retaining the projectile upon the pivoted plate until the releasing means is operated.

3. A target including a sheet of rubber and the like having an aperture therein, a substantially vertical tube communicating at its upper portion with said aperture, a pivoted plate normally closing the lower end of the tube, an electrically operated signal associated with the target, a circuit connected to the signal, circuit closing means in the circuit arranged to be operated by said pivoted plate, the pivoted plate being so arranged that a projectile entering the tube through said aperture will come to rest upon the plate and tilt the same sufficiently to close the circuit closing means without releasing the projectile, and manually operated means for permitting further tilting of the plate to permit the projectile to fall therefrom.

In testimony that I claim the above, I have hereunto subscribed my name,

MILO E. HUTH.
